UNITED STATES PATENT OFFICE.

JULIET L. RYAN, OF NEW YORK, N. Y.

SOAP-GRATER.

SPECIFICATION forming part of Letters Patent No. 630,413, dated August 8, 1899.

Application filed July 5, 1898. Serial No. 685,214. (No model.)

To all whom it may concern:

Be it known that I, JULIET L. RYAN, a citizen of the United States, and a resident of New York city, county of New York, and State of New York, have invented certain new and useful Improvements in Soap-Boxes, of which the following is a specification, reference being had to the accompanying drawings, forming a part thereof, in which similar letters and numerals of reference indicate corresponding parts.

This invention relates to improvements in soap-boxes adapted to discharge soap in a grated or powdered state; and the object of the invention is to supply a device of this class so constructed as to be applicable for the consumption of any ordinary cake of soap, whereby a consumer can secure a supply of powdered soap equal to his requirements without the necessity of handling the cake, thus providing an efficient device adapted for use in public places and which obviates the danger of spreading disease by allowing a number of persons to handle a cake of soap.

The invention will be hereinafter fully described, and specifically set forth in the annexed claim.

In the accompanying drawings, forming part of this specification, Figure 1 is a vertical sectional elevation of my improved device, and Fig. 2 is a sectional plan view taken on the line *x-x* of Fig. 1.

In the practice of my invention I provide, primarily, a box A, preferably of rectangular contour. The said box is open at the top and is provided with a hinged lid B for closing the same. A discharge-opening *a* is also provided at the bottom of the box for feeding the powdered or grated soap, as will be herein-after described.

Located within the box near the front thereof is a sliding grater C, which is adapted to move vertically within ways or guides *c*, secured to the side walls of the box, whereby lateral motion of the grater is prevented. As a means for operating the grater, a rack D is secured thereto and engages with a segmental series of teeth *e* of a pinion E, the said pinion being mounted upon a shaft F, which is operated by means of a crank G. The grater C is maintained normally in its downward position, as illustrated in Fig. 1 of the draw-

ings, by means of a bow-spring H, which is secured to the lid B by means of the arm *h* thereof, the free arm *h'* of the bow-spring resting upon the upper edge of the grater C. Located to one side of the spring H and also secured to the lid B is a curved plate-spring I, which rests upon the top of the cake of soap to prevent upward movement thereof. Another plate-spring J is secured to the rear wall of the box and bears upon the back of the cake of soap to feed the same forwardly during the process of its consumption. The normal shape and position of this back spring is illustrated by dotted lines *J'*, Fig. 1 of the drawings, which illustrates that the soap can be fed forwardly until it is entirely consumed.

The lid is normally closed by means of a hasp 2 and a lock 3, whereby the soap cannot be surreptitiously removed from the box; but the location of the springs H and I upon the lid admits of easy access to the box for the purpose of placing the cake of soap when the lid is thrown open.

The device is further supplied with a supporting-standard K.

In the operation of the device the pinion E is rotated in the direction of the arrow 4, Fig. 80 1 of the drawings, until the required amount of powdered soap is supplied, the rotation of the said pinion causing the grater to move in an upward direction while the rack is in engagement with the teeth *e*; but when the rack 85 contacts with the smooth segment *e'* of the pinion the spring H will throw the grater down into its normal position, and by this action any particles of soap adhering to the grater or to the outlet of the casing will be 90 automatically shaken or thrown out, and this shaking action entirely prevents clogging of the parts and comprises an essential feature of my invention.

Having thus described my invention, what I claim as new, and desire to secure by Letters Patent, is—

A soap-box for supplying powdered soap from an ordinary cake, comprising a casing containing springs for controlling the cake, a 100 spring-actuated reciprocating grater, and a rack and pinion for moving the grater, the said pinion being supplied only with a segmental series of teeth, whereby during the

revolution thereof, the spring-actuated grater is operated independently of the pinion and in a direction opposite to the direction of the movement supplied by the said pinion, substantially as shown and described.

5 In testimony that I claim the foregoing as my invention I have signed my name, in pres-

ence of two witnesses, this 28th day of June, 1898.

JULIET L. RYAN.
